CARD PUNCHING MACHINE

Charles R. Doty, Poughkeepsie, Herman J. Klotz, Endicott, and Theodore D. Koranye, Vestal, N. Y., assignors to International Business Machines Corporation, New York, N. Y., a corporation of New York

Original application February 14, 1947, Serial No. 728,600, now Patent No. 2,569,805, dated October 2, 1951. Divided and this application July 1, 1950, Serial No. 171,602

4 Claims. (Cl. 164—113)

1

This application is a division of the application of Charles R. Doty, Herman J. Klotz, and Theodore D. Koranye, Serial No. 728,600, filed February 14, 1947, now Patent No. 2,569,805, granted October 2, 1951.

This invention concerns improvements in card punching machines of the type shown in the patent to Fred Lee and George F. Daly, No. 1,976,618, issued October 9, 1934, and the present improvements comprise structural changes which enable punching of at least two holes in each card column successively under selective control as to columns, without an intervening carriage escapement, during multiple punching in a column.

The card punching machine of the type shown in the above patent is normally adapted to space the card carriage with the card after punching a single hole in a column under control of a keyboard, but double holes can be punched in the last column in No. 1,976,618. At times there are requirements that two holes be punched in the same card column in said patent. It is desirable, for example in said patent, to perforate a column to represent a digit and also to punch out the O, X and R holes which are used for control purposes. Occasionally in Patent No. 1,976,618 it is desirable to punch holes in combination to represent alphabetical data by using two keys. There are, of course, key controlled card punching machines other than Patent No. 1,976,618 designed to effect this operation so that single key depressions effect combinational hole punching but occasionally it is desirable in the form of key controlled punching machines shown in the aforementioned patent to punch one or more adjacent card columns to effect this alphabetical code punching by using two keys. Previously this has been sometimes attained by back-spacing the carriage after punching the first hole for enabling the punching of the second hole in the same column. However, in Schaaf, No. 1,300,491, granted April 15, 1919, double punching in a column could be effected by holding down the space key and hitting two keys for punching holes in the same column. This double punching could be effected for a selected plurality of columns.

Understanding, therefore, the need of combinational hole punching in a card punching machine which is normally adapted to punch a single hole per column in columns other than the last column, it is the main object of the invention

2

to provide means to condition the punching machine so that multiple hole punching can be effected in a series of adjacent columns other than the last card column by successive key depressions moving two keys for double-hole punching in a card column without an intervening operation of the escapement mechanism after the first key depression.

A further object of the present invention is to condition the machine for not only effecting multiple hole punching in a single column by the mode of operation first described but to condition the machine so that this mode of operation can be carried out for a successive number of columns.

In carrying out the object of the present invention the escapement mechanism of the card carrying carriage is conditioned so that it will maintain and hold the card carriage from movement after the first card hole punching operation. After the second hole punching by the next key depression the escapement mechanism will be restored to its normal condition, preferably being so conditioned by the operation of a supplemental key operated after the second hole punching operation.

To condition the machine for multiple hole per column card punching for a plurality of successive columns it is preferable to employ the customary column readout structure of the card punching machine so that at a predetermined card column a plug connection from such readout causes the conditioning of the escapement mechanism to lock the card carriage against movement after each first card hole punching for each of the successive card columns. By means of another plug connection from the column readout the escapement mechanism is again restored to its normal condition for punching a single hole in each of the following card columns, which is the normal operation of card punching machines of the type in which the present improvements are preferably embodied.

Other objects of the invention will be pointed out in the following description and claims and illustrated in the accompanying drawings, which disclose, by way of example, the principle of the invention and the best mode, which has been contemplated, of applying that principle.

50 In the drawings:

Fig. 1 is a longitudinal sectional view of a punching machine of a well known form and shows particularly the punch operating mech-

anism, as well as the readout contact strip for determining which card columns are to be selected for double hole punching.

Fig. 2 is a view in side elevation showing the internal contact operating mechanism controlled by the keys of the auxiliary keyboard.

Fig. 3 is a perspective view showing the preferred means for suppressing the operation of the escapement pawls when the card carriage is to be held for multiple hole punching in successive card columns.

Figs. 4 and 5 are detail views showing in different positions the means for operating the floating cam contacts in the card punch.

Fig. 6 is an electrical wiring diagram of the machine which is restricted to a showing necessary to understand the present invention.

Auxiliary keyboard

The auxiliary keyboard K may comprise the structure shown in the patent to O. B. Shafer, No. 2,815,741, issued April 6, 1943, and is also shown on Fig. 2 herein for convenience. The contacts closed by the keyboard are shown in the wiring diagram of Fig. 6.

In the numerical keyboard there is provided a key 117 for each of the digits 0 to 9 inclusive and two keys, the contacts 124 of which are designated 11 and 12 in Fig. 6 for punching corresponding X(11) and R(12) index point positions of a card in the punching machine. Also mounted on this keyboard are supplementary keys which include a space key 117S (Fig. 6). Depression of any key 117 will rock a bell crank 119 which, through a pin and slot connection, will move a slider 120 towards the left as viewed in Fig. 2. Each of the sliders cooperates at its end with a bail 121 to turn the same counterclockwise and the bail in turn will rock a lever 122 to close a pair of bail contacts 123. Bail contacts 123 are common to all of the keys 117 and are closed by the depression of each of said keys. Contacts 123 are shown in the wiring diagram in Fig. 6 as well as contacts 124 which are individual to each key and are closed upon depression of the key. There is one slider 120 for each of the keys, which slider is urged to the left upon depression of its associated key and for each slider there is a lever 125 which is rocked to close the associated pair of contacts 124. The key 117S operates a similar slider 120 and its lever 125 closes two pairs of contacts not shown in Fig. 2 but designated as contacts 124S1 and 124S2 in Fig. 6.

Card punching machine

The card punching machine used in connection with the present invention is of the type shown in the patent to Fred Lee and George F. Daly, No. 1,976,618, dated October 9, 1934, and only so much of the operation thereof will be explained as is necessary for an understanding of its operation in connection with the present invention.

In general, the punching machine (Fig. 1) contains a feed magazine 53 from which cards are fed singly from the bottom of the magazine as is well known by a picker which feeds the cards to a position under punches 55 and in the present machine the carriage is preferably returned to column 1 of the card to the punches, preparatory to receiving the perforations effected by the first manual punching operation. From this position the card is engaged at its rear edge by a pusher 54 mounted upon an escapement rack 56 which, for each operation of the punches permits the

advance of the card one column. A series of magnets 45 is adapted to select the punches 55 for actuation in the following manner: Associated with each magnet 55 is a pivoted armature 57 whose free end is connected to a rod 58 which, through a bell crank 59, moves an interposer bar 60 to the left where it cooperates with a punch bar or plate 61. The forward movement of the interposer bar 60 is adapted to rock a bail 62 pivoted on a rod 63 and which bail is connected to a spring-pressed depending link 64 whose lower free end is adapted to engage and close the punch magnet contacts 65. This, as will be described in connection with the wiring diagram, closes a circuit through a punch magnet 66 which then attracts its armature 67 and through a link and bell crank connection 52 will draw downwardly on the pivoted punch bar or plate 61 to force the selector interposer against the associated punch, thus perforating the card. When the armature 67 is attracted by punch magnet 66 a projection 52a on the horizontal link 52 closes contacts 65a, which contacts are also shown in Fig. 6 of the wiring diagram. Such contacts are closed after perforating the card and before the punch carriage spaces to the next column position.

In the present machine the energization of the punch selector magnets 45 of which there are twelve, one for the digit positions 0-9 inclusive and the 11 and 12 index point positions is under control of the keys of the auxiliary keyboard.

As is fully shown in the patent to Lee et al., No. 1,976,618, when the armature 67 reaches the limit of its movement to the right the link 64 will be moved by a projection to become disengaged from one of the spring blades of contacts 65 to permit such contacts to open, thereby deenergizing the punch magnet 66 which will then release its armature 67, allowing a spring 68 to rock the plate 61 upwardly and permit the selected interposer 60 to rise and thereafter be restored to normal position by a spring 69.

Escapement mechanism

The escapement mechanism 15 is shown herein in some detail in Figs. 4 and 5 but is fully shown and described in Patents Nos. 1,976,618 and 1,426,223. It will suffice to say that when an interposer 60 is depressed it will rock a bail 70 (Fig. 1) attached to a shaft 71 and the rocking of this shaft will actuate the escapement mechanism to space the card carriage a single column. Associated with the escapement mechanism are contacts 128a and 128b (see Figs. 4, 5, and 6). These contacts correspond to similarly designated contacts 128 in Patent No. 1,976,618. These contacts are normally closed but are opened by the escapement mechanism during the time that the card carriage is spacing to the next column position (see Fig. 4). When this column position has been reached both of the contacts 128a and 128b close (see Fig. 5). Contacts 128a and 128b are utilized in circuits to be subsequently described in connection with the wiring diagram of Fig. 6.

Column selector

The column selector for the machine illustrated herein is also well known and is shown in the patent to George F. Daly et al., No. 2,016,706, dated October 8, 1935. As shown in Fig. 1 as well as Fig. 6, it consists of a movable contact brush 72 carried by the punch carriage engageable with a reading strip comprising a common contact strip 73, contact points 74, and plug sockets, some of which are connected by plug connections so as to

cause certain functions to be performed when the carriage is at certain column positions in a manner to be subsequently explained. The contact points 74 are individually connected to the plug sockets 75 of a plugboard shown in Fig. 6 and the plug sockets correspond to the card column positions of the card carriage.

Punching under control of the auxiliary keyboard

The operation of the machine will now be given mainly in connection with the wiring diagram of Fig. 6 and there will now be described the circuits which are operative for causing punching of a card under control of the auxiliary keyboard K. As previously described, when the digit keys of the auxiliary keyboard are operated the individual contacts 124 (Fig. 2) will be closed as well as the bail contacts 123. Closure of contacts 124 will select punch selector magnets 45 for energization. Current is supplied by the power supply lines 130, and 131 (Fig. 6) and many of the circuit connections are completed through contacts 102 (Figs. 1 and 6) which are well known latch contacts in the card punching machine. When a key is depressed a circuit will be completed from the line 131, through latch contacts 102, wire 133, through punch bed contacts 421 and through the magazine contacts 418. These two last mentioned contacts correspond to the similarly designated contacts in Patent No. 2,285,289, and contacts 421 are shown in Fig. 1 as well. As long as there are cards in the supply magazine contacts 418 (Fig. 1) are closed and when a card is in position on the card carriage contacts 421 are closed by a card lever 420. The circuit then extends from contacts 421 and 418, thence through bail contacts 123, through transfer contacts R35a, at normal, thence to a wire 134 which is connected to one side of all the key operated contacts 124. The closure of said contacts 124 by the operated key will then extend the circuit through the individual connecting wire 135 in a cable to the corresponding relay 140 and punch selecting magnet 45. The wiring connection from the other side of the punch selector magnets 45 is through the R14 relay to the line 130 for punch selecting magnets 1-9 inclusive, and for punch selector magnets 0, 11 and 12 the circuit is completed to line 130 through the R13 relay. Punch selector magnets 45 will now shift the related interposer 60 (Fig. 1) to select the desired punch 55 for operation.

The circuit to energize the punch magnet 66 to actually effect the punching operation is from the line 131 through latch contacts 102, punch magnet contacts 65, wire 138, punch magnet 66, wire 139 to line 130. Punch magnet 66 then attracts its armature 67, opening punch magnet 66 contacts 65 and deenergizing punch magnet 66. A supplemental circuit is provided to maintain punch magnet 66 energized for a time determined by the closure of floating cam contacts 128a. This circuit extends from punch magnet 66 through either relay contacts R13a or R14a, wire 137, floating cam contacts 128a, wire 136, latch contacts 102, to line 130.

A holding circuit is provided for the energized relay 140 which extends through the respective contacts 140b to a line 142, thence through relay contacts R57d, through the floating cam contacts 128b, wire 136, latch contacts 102 back to line 130. Therefore, relays 140 which are used for a purpose explained in the aforementioned application are retained energized until the floating cam 75 A hold circuit for the R35 relay is maintained

contacts 128b open which is when the card carriage has skipped to the next column position.

Means to effect multiple hole punching in one or more card columns

Occasionally there is a requirement for perforating a card column with more than one hole since it is desirable, for example, to perforate the column to represent a digit and also to punch out the 11th or 12th index point positions which respectively denote X and R.

The present machine incorporates a selectively operated arrangement which controls double (or more) punching for not only a single column but also for a plurality of successive columns. According to the first column where multiple punching is to start, a plug connection 181 is made from the desired plug socket 75 (Fig. 6) to the plug socket 180 of the R57 relay, thus completing an energizing circuit from line 131, through latch contacts 102, wire 136, floating cam contacts 128a, wire 137, common contact bar 73, brush 72, contact point 74, plug socket 75, plug connection 181 therefrom to a plug socket 180, through R35d relay contacts, relay R57, to line side 130, thus energizing R57 relay at this card column position of the carriage. A hold circuit for the R57 relay is made through the R57a contacts, R58a contacts now closed, wire 151, through the latch contacts 102 to line side 131. Also, through the R35d and R36b contacts the energizing circuit to the multiple punch solenoid 170 is completed through wire 139 to line 130. Energization of the multiple punch solenoid 170 (see Fig. 3) operates the escapement mechanism so that the holding dog is held down to prevent escapement to the next column.

The multiple punch solenoid 170 moves a bell crank lever 500 clockwise about its pivot stud 501, the plunger of the solenoid having a pin 502 engaging in a slot 503 of the bell crank. A thrust bar 504 pivoted at 506 to the bell crank 500 rocks counterclockwise an arm 507 on the escapement dog control shaft 508. A pin 509 on a casting secured on this shaft engages in a slot 510 of the escapement dog 511 and rocks this dog into engagement with the rack bar 512. At the same time a pin 513 engaging an elongated hole 514 of the second escapement dog 515 lifts the latter out of engagement with the rack bar and allows it to jump forward over the next tooth of the rack bar, under the force of spring 516. The rack bar is thus locked until the multiple punch solenoid 170 is deenergized.

However, when solenoid 170 is deenergized its release will enable the escapement mechanism to operate in the regular way to space to the next column. The R57b contacts (Fig. 6) close so that, as will be later explained, the R36P relay coil is picked up when space key 117S is depressed. R57d contacts which are normally open close to thus transfer the hold circuit for the relays 140 through the R35a contacts and the latch contacts 102 back to line 131. The machine has now been conditioned for enabling multiple hole punching in a column. The first digit key of the auxiliary keyboard is depressed to punch the first hole and in the manner explained the punch magnet 66 will effect the desired hole punching. Energization of the punch magnet 66 effects the closure of the armature contacts 65a and a circuit will be completed from line 131 through latch contacts 102, wire 133, transferred armature contacts 65a, R35 relay, and wire 173 to line 130. A hold circuit for the R35 relay is maintained

through the transferred R35b contacts, bail contacts 123, magazine contacts 418, punch bed contacts 421, wire 133, latch contacts 102 back to line 131. When R35 relay energizes for each digit key operation the R35d contacts open to tend to open the energizing circuit of the R57 relay but the latter is still energized by its holding circuit. The second digit key depression of the auxiliary keyboard is now made by the operator to punch the second hole in the same column and a repetition of the above operations occurs. After multiple punching in each card column the space key 117S of the auxiliary keyboard is then operated and recalling that the R57b contacts are now closed, depression of the space key 117S will complete a circuit from line 131 through latch contacts 102, wire 133, punch bed contacts 421, magazine contacts 418, auxiliary space key contacts 124S1, R35b contacts, space key contacts 124S2, a wire 135 in the cable, through R57b contacts now closed to R36P coil to line 130. The hold circuit for the R36H coil is effected through the R36a contacts, a wire 135 in the cable, the space key contacts 124S2, R35b contacts, auxiliary keyboard space contacts 124S1, magazine contacts 418, punch bed contacts 421, wire 133, latch contacts 102 to line 131. The R36b contacts open the circuit to the punch space solenoid 170 to release the escapement mechanism and the card spaces to the next column. When the space key 117S is released the R36 relay drops out to again condition the machine for effecting multiple hole punching on the second column. In the above manner one or more successive card columns can each be multiple punched and in the last column of the field a plug connection 182 is made from such column plug socket 75 to plug socket 174 of the R58 relay. The latter opens the R58a holding contacts, thus deenergizing the R57 relay and restoring the escapement mechanism of the machine to a condition for enabling single hole column punching for successive columns.

While there have been shown and described and pointed out the fundamental novel features of the invention, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a card punching machine for double punching successive columns followed by single hole punching for the same card carried by a card carriage, the combination of a digit keyboard to effect card punching operations, conditioning means initially effective by means actuated at the card carriage at the first column position of said successive columns double punching is to be effective, means for effecting card column spacing operations, means controlled by said conditioning means and operable at the first column position and successive column position at which double punching is to be effected to suppress the operation of said column spacing means to enable double punchings in said first column position and successive column positions by said keyboard, means for disabling by means at the card carriage said preceding means upon completion of double punching at each column position to cause the column spacing means to automatically space the card to the next column to be double punched, and other means

actuated by the card carriage for disabling the conditioning means for conditioning the machine at the final column position of successive columns at which double punching should be terminated and single hole per column punching should be initiated for a following column of the same card.

2. In a card punching machine for double punching successive columns followed by single hole punching for the same card, the combination of a digit keyboard to effect card punching operations by successive column spacing of a card carriage, conditioning means initially effective by means at the card carriage at the first column position of said successive columns double punching is to be effective, means for effecting column spacing operations, means controlled by said conditioning means and operable at the first column position of said card carriage and successive column positions of the carriage at which double punching is to be effected to suppress the operation of said column spacing means to enable double punchings in the first column and each of the successive column positions by said keyboard, key controlled means operable after double punching each column for disabling said preceding means upon completion of double punching at each column position to cause the column spacing means to automatically space the card carriage to the next column to be double punched, and other means actuated by the card carriage for disabling the conditioning means for conditioning the machine at the final column position of said card carriage double punching should be terminated and single hole per column punching should be initiated for following columns of the same card.

3. In a card punching machine for multiple punching successive columns followed by single hole punching for the same card carried by a card carriage, the combination of a digit keyboard to effect card punching operations, conditioning means initially effective by means at the card carriage at the first column position of said successive columns multiple punching is to be effective, means for effecting column spacing operations, means controlled by said conditioning means and operable at the first column position and successive column positions at which double punching is to be effected to suppress the operation of said column spacing means to enable multiple punchings in said first column and each of the successive column positions, means for disabling said preceding means upon completion of multiple punching at each column position to cause the automatic spacing of the card to the next column to be double punched, and other means at the card carriage for disabling the conditioning means and said suppressing means for conditioning the machine at the final column position of said successive columns multiple punching should be terminated to enable single hole per column punching should be initiated for following columns of the same card.

4. In a card punching machine for double punching successive columns followed by a single hole punching for the same card carried by a card carriage, the combination of a digit keyboard to effect card punching operations by selected punches, conditioning means initially effective by means at the card carriage at the first column position of said successive columns double punching is to be effective, means for effecting automatic relative column positions of said card

and punches for successive column punching operations, means at the card carriage operable at the first column position and successive column positions to suppress the operation of said preceding means to enable double punchings in the same column position by said keyboard, means at the card carriage for disabling said means for effecting relative column positions upon completion of double punching at each column position to automatically space the card to the next column to be punched, and other means at the card carriage for disabling said conditioning means for conditioning the machine at the final column position of said successive columns double punching should be terminated and en-

able that single hole per column punching should be initiated for following card columns of the same card.
